UNITED STATES PATENT OFFICE.

SAMUEL W. ROTHROCK, OF NEW YORK, N. Y.

WALL AND FLOOR PLUG.

Application filed August 22, 1922. Serial No. 583,500.

To all whom it may concern:

Be it known that I, SAMUEL W. ROTHROCK, a citizen of the United States, and a resident of the city of New York, county 5 of Queens, and State of New York, have invented a new and useful Improvement in Wall and Floor Plugs, of which the following is a specification.

The object of my invention is to provide 10 a wall or floor plug which may be used in any desired location and which may be readily located when in use. This and other objects are accomplished by my invention, some embodiments of which are 15 hereinafter more particularly set forth.

For a more detailed description of my invention, reference is to be had to the accompanying drawings, forming a part hereof, in which—

20 Figure 1 is a plan view of a wall plug embodying my invention.

Figure 2 is a front elevation of the same.

Figure 3 is a sectional view taken on the line 3—3 of Figure 1, looking in the 25 direction of the arrows.

Figure 4 is a sectional view, taken on the line 4—4 of Figure 1, looking in the direction of the arrows.

Figure 5 is a modified form of a floor 30 plug embodying my invention when inserted in a floor, and

Figure 6 shows the same as adapted to be used in a wall.

Throughout the various views of the 35 drawings, similar reference characters designate similar parts.

My improved wall or floor plug 1 is provided with a wooden filler 2 and a metal casing 3 which may be any desired shape 40 according to the size and character of the filler. In the embodiment of my invention shown in Figures 1 to 4 inclusive, this plate 3 is bent back upon itself at 4 and flanged at its ends 5 and provided with end 45 ears 6 which take over the parallel surfaces. The plates are also provided with a number of indentations 7 which give the mortar or concrete a chance to grip, and hold the filler in the plug.

50 When such wall plugs are used in the conventional manner they are covered by wood grounds or finish, and as they are small it is often hard for a carpenter to locate them. To make the work of location

easier and more certain, I provide a finding 55 wire 8 which extends about the wood 2 and is caught between the wood and the adjacent metal sheet 3 so as to be firmly held. This wire 8 should extend from the center of the filler 2.

If desired, the plug may be made with a metal sheet 3, as shown in Figures 5 and 6, with walls which are angular and bent inwardly and then the filler 2 is made to correspond. In this embodiment the filler 65 is gripped very firmly, as it is held in what might be termed a dovetailed joint. This is a good construction for floors where strips of wood 9 may be held in place by a nail 10 which passes into the filler 2.

When the structure shown in Figures 1 to 4 inclusive is used, the wall plug 1 is set in mortar 11 between bricks or other masonry 12, as soon as the mortar is put in place and before the brick or other masonry is placed on the mortar. When a floor plug is used, as shown in Figure 5, this plug 1 is inserted while the concrete 13 is soft. In the preferred form of floor plug, I provide a cap 14 as shown in Figure 5, which is made of thin sheet metal and protects the wood from splitting. In this structure, a finding wire 8 may be employed, in which event the wire passes through a suitable perforation in the cap 14.

While I have shown and described some embodiments of my invention, it is obvious that it is not restricted thereto, but that it is broad enough to cover all structures that come within the scope of the annexed 80 claim.

Having thus described my invention, what I claim is:

A wall or floor plug comprising a filler of fibrous material, and a metal casing surrounding the filler on all sides but one, the casing being provided with outwardly turned flanges at its open end and being further provided with non-perforating depressions, which engage with the filler on 100 the inside of the casing and are adapted to be engaged by the mortar or concrete in which the plug is set.

In testimony whereof, I have hereunto set my hand and seal this 14th day of 105 August, 1922.

SAMUEL W. ROTHROCK.
